DESIGN FOR A TRAILER

William J. Parrish, Detroit, Mich., assignor to Curtiss Aerocar Company, Inc., Opa Locka,
Fla., a corporation of Florida

Application June 6, 1933. Serial No. 48,299

Term of patent 14 years

To all whom it may concern:

Be it known that I, WILLIAM J. PARRISH, a citizen of the United States, residing at Detroit, in the county of Wayne and State of Michigan, have invented a new, original, and ornamental Design for Trailer, of which the following is a specification, reference being had to the accompanying drawings, forming a part thereof.

Referring to the drawings:

Fig. 1 is a side view of a trailer,
Fig. 2 is a top view thereof, and
Fig. 3 is a perspective view taken from a point forward of and slightly above the trailer.

I claim:

The ornamental design for trailer as shown.

WILLIAM J. PARRISH.
